REED AND HIGHSTED FILING AND SHARPENING DEVICE FOR SCISSORS AND SHEARS, HAVING AN ADJUSTABLE SUPPORT OR FRAME WHICH IS ADJUSTED TO THE ANGLE OF THE SCISSORS BLADE AND WHICH IS PROVIDED WITH A SCREW MECHANISM FOR ADJUSTING THE ANGLE OF THE SCISSORS BLADE, AND WHICH IS PROVIDED WITH A SCREW MECHANISM FOR ADJUSTING THE ANGLE OF THE SCISSORS BLADE.

UNITED STATES PATENT OFFICE

2,466,410

SHEARS SHARPENING DEVICE
Ora H. Garrison and Frank G. Leistner, Evansville, Ind.

Application May 23, 1946, Serial No. 671,759

3-Claims. (Cl. 76—82.2)

This invention relates to scissors or shears sharpeners; and aims to provide an adjustable support or frame to which the scissors blade may be clamped in the desired position and with the cutting edge at the proper angle, so that a file which rests upon a roller which in turn is longitudinally slidable for positioning along its fixed shaft and is provided with end flanges, may be worked over the cutting edge to sharpen the same.

The above broad as well as additional and more specific objects will become apparent in the following description, wherein characters of reference refer to like-numbered parts in the accompanying drawings. It is to be noted that the drawings are intended to serve the purpose of illustration only, and that it is neither desired nor intended to limit the invention necessarily to the exact details of construction shown excepting insofar as they may be deemed essential to the invention.

Referring briefly to the drawings,

Fig. 1 is a front elevational view of the device, showing how a scissors blade may be clamped in the front two clamp plates.

Fig. 2 is a plan view of the same.

Fig. 3 is an end elevational view of the device.

Fig. 4 is a cross-sectional view taken on the line 4—4 of Fig. 1.

Fig. 5 is a cross-sectional view taken on the line 5—5 of Fig. 1, showing the manner in which a file is used.

Referring in detail to the drawings, the numeral 10 indicates a frame or support comprising the vertical apron 11 having the upper portion 12 thereof of greater width and provided with the two end wings or walls 13 and 14 bent at right angles thereto. The apron 11 is provided with a horizontal extension 15, and the device is adapted to be mounted on a bench or table by having the latter register between the wings 13—14 and the extension or tongue 15, in an obvious manner.

The wings 13 and 14 are provided with aligned slots 16 and 17, respectively, extending partway down the walls, substantially as shown. Each of a pair of substantially identical plates 18 and 19 is provided with a longitudinal slot 20 of substantially the same width as the slots 16—17, in the lower portion thereof. Near the upper ends of these plates openings 21 are provided, receptive of a bolt 22 having the head 23 on one end and having the other end threaded and provided with a nut 24. Screw bolts 25 pass through the slots 16, 20 and 17, 20, and, with the aid of

wing nuts 26, clamp the plates 18, 19, against the wings 13, 14, respectively, on the outer sides of the latter, with the bolt 22 passing through the slots 16, 17. Thus it is apparent that the bolt 22 may be raised or lowered at will and locked in the desired position.

A roller or sleeve 27, provided with end flanges 28, is rotatably as well as slidably mounted on the bolt 22. A longitudinal slot 29 is provided

10 through the apron wall 12 near the upper edge thereof. A plate 30, similar to the plates 18 and 19 and having the same slot 20 therethrough, is mounted on the outside of the wall 12 by passing the screw bolt 31 through the slots 20, 29, and the

15 position of the plate may obviously be varied in the mutually right-angle directions represented by the slots 20, 29, the screw bolt 31 having the wing nut 32 thereon.

A third plate 33, having a longitudinal slot 34 therethrough, is secured against the wall 12 by passing a screw bolt 35 through the slot 34 and an opening 37 in the wall 12 and tightening the wing nut 36 on the bolt 35. A boss 39 is rigid on the plate 33 substantially as shown, and acts

20 as a spacer to hold the plate 33 in inclined position when locked against the wall 12. The upper edge of the plate 33 is beveled, as shown at 40.

The manner in which the device is used, is as follows. A blade of a pair of shears 41, shown at 30 42, is clamped in the device between the upper ends of the plates 30, 33 and the wall 12; it is to be noted that the boss 39 tilts the plate 33 at an angle substantially equal to the angle between the two sides or walls of the blade 42, thus insuring a tight grip on the blade. The bolt 22 is then positioned at the proper horizontal level

35 so that a file shown in broken lines at 43 in Fig. 5, when resting on the roller 27 and sloping downward toward the blade 43, will rest flush on the cutting edge 44 of the latter. Then, as the file is worked back and forth across the edge 44, the roller 27 is free to rotate as well as slide along the bolt 22, the file being all the time maintained at the proper angle for sharpening the blade 42.

40 Thus a perfect filing and sharpening of the cutting edge 44 is achieved, with the elimination of chance or the need for skill on the part of the worker to maintain the file always at the proper angle, which would in fact be quite impossible without using the device set forth in the drawings.

45 Obviously, modifications in form and structure may be made without departing from the spirit and scope of the invention.

As an aid in pre-setting of the bolt 22 so that

the file, when applied to the roller and the cutting edge of the blade may be at the proper angle, graduations 45 may be marked on the wing 13 or on the other wing, as well as on either or both sides of the wing. These graduations may be made to read in degrees or in any other suitable units.

We claim:

1. A device of the class described comprising a frame having a front wall and two spaced end side walls extending at substantially right angles from said front wall, said side walls having slots therethrough lying in a common plane, a bolt having the extremities passing through said slots, locking means for locking said bolt at any desired substantially horizontal position within said slots, said bolt having a roller rotatably and slidably mounted thereon, and means for locking a cutter blade against said front wall at a level below the level of said bolt, said first-named locking means comprising plates having openings therethrough receptive of the ends of said bolt and having additional openings therethrough, screw bolts passing through said additional openings and said slots, and nuts on said screw bolts.

2. The device set forth in claim 1, said last-named means comprising a number of horizontally spaced plates each having an opening therethrough, said front wall having a like number of openings therethrough, a like number of screw bolts, each of said last-named screw bolts passing through one of said front wall openings and one of said last-named plate openings, nuts on said screw bolts, one of said plates having a rounded spacer projection on that side thereof which faces said front wall, said projection being positioned below the said opening through said last-named plate.

3. A device of the class described comprising a frame having a front wall and two spaced end side walls at substantially right angles to said front wall, said side walls having slots therethrough lying in a common vertical plane, a bolt

having its extremities passing through said slots, locking means for locking said bolt at any desired substantially horizontal position within said slots, said bolt having a roller rotatably and slidably mounted thereon, means for locking a cutter blade against said front wall at a level below the level of said bolt, said first-named locking means comprising plates having openings therethrough receptive of the ends of said bolt and having additional openings therethrough, screw bolts passing through said additional openings, nuts on said screw bolts, said last-named locking means comprising a number of horizontally spaced plates each having an opening therethrough, said front wall having a like number of openings therethrough, a like number of screw bolts, each of said last-named screw bolts passing through one of said front wall openings and one of said last-named plate openings, nuts on said last-named screw bolts, one of said last-named plates having a rounded spacer projection on that side thereof which faces said front wall, said projection being positioned near the lower edge of said one of said plates.
